LACE CLOCK MECHANISM FOR FULL FASHIONED KNITTING MACHINES

Filed June 20, 1930

UNITED STATES PATENT OFFICE

MELCHIOR ZWICKY, OF BERKSHIRE HEIGHTS, PENNSYLVANIA, ASSIGNOR TO TEXTILE MACHINE WORKS, OF WYOMISSING, PENNSYLVANIA, A CORPORATION OF PENNSYLVANIA

LACE-CLOCK MECHANISM FOR FULL-FASHIONED KNITTING MACHINES

Application filed June 20, 1930. Serial No. 462,495.

My invention relates to improvements in lace clocking mechanisms of the type used on straight or full fashioned knitting machines.

As well known, lace clocking mechanisms 5 of this type essentially comprise a plurality of point rods and pattern controlled shifting means therefor.

Heretofore, the ends of the point rods have been contactingly held against an actuating 10 member or shifting plate by either short helical compression springs mounted directly on the rods, or comparatively long tension springs attached to the sides of the latter.

The spring action obtained in this manner 15 has been found unsatisfactory; in the first instance because it was too stiff and variable, causing excessive wear between the rod's ends and actuating plate, and owing to the necessity of removing the rods in case of spring 20 breakage; and in the second instance because of undesirable sidewise pull exerted against the rods.

The primary object of my invention is to 25 provide novel and simple means overcoming such faulty spring action on the rods, and I accomplish this by the use of a movable member for each rod adapted to keep the latter constantly in contact with the shifting means, and actuating means for said movable mem- 30 bers.

The invention comprises the novel elements, features of construction and arrangement of parts in cooperative relationship as fully disclosed by the following detailed description and accompanying drawing of one embodiment thereof, reference to which will 35 make the above and other objects, as well as attendant advantages, more readily apparent.

Referring to the drawing:—

40 Fig. 1 is a fragmentary front elevational view of the point rods, and associated parts of a lace clocking attachment for full fashioned knitting machines, and shows my invention applied thereto.

45 Fig. 2 is a fragmentary plan view of the right hand end of Fig. 1.

Fig. 3 is a sectional view taken substantially as indicated by the arrows 3—3 on Fig. 1.

50 The point rods 4, 5 and 6 are provided

with the usual and varied number of points P which cooperate with the needles in producing the lace clocks, and are mounted for reciprocatory movement in well known manner; their adjustable ends 4a, 5a, and 6a abutting the common rod actuating plate 7 which is moved by pattern controlled shifting mechanism, not shown.

A bracket or mounting 8 is fixed to the front narrowing shaft 9 of the machine, as shown, which is adapted to carry presser elements or levers 10, 11 and 12. These levers have integrally formed abutment parts or enlargements 10a, 11a and 12a at their lower ends, which are normally in contact with and press against the rounded adjustable tips 13, 14 and 15 of the point rods 4, 5 and 6 respectively. Lever 10 is pivoted on a pin 16, fixed in mounting 8 by a set screw 17, while levers 11 and 12 are fulcrumed on a common pin 18, fixed in mounting 8 by a set screw 19.

Tension springs 20, 21 and 22 are connected to the upper ends of levers 10, 11 and 12 respectively and to a pin 23 secured to one end of an arm 24 which is bolted to the front narrowing shaft 9 of the machine.

The power or pull applied to the upper ends of the levers by the springs, is multiplied and transmitted by the levers to the point rods in the form of pressure exerted axially thereof. This pressure is substantially uniform owing to the long actuating springs, and can be varied within wide limits, by either the substitution of other springs, or by providing adjusting means such as indicated at 25.

It will be noted, that the pressure on the point rods 4, 5 and 6 remains constant when they are turned for the purpose of moving the points P to and from their lower or active position and into or out of operative relation with the needles, in the well known manner, owing to the contacting connection between the rod ends 13, 14 and 15 and the presser lever enlargements 10a, 11a and 12a.

Of course, the device shown and described can be changed and modified in various ways and adapted for other similar purposes without departing from the invention herein set forth and hereinafter claimed.

I claim—

1. In combination with a full fashioned knitting machine having a lace-point-rod shifting plate, a rockable lace-clock mechanism comprising a narrowing shaft having spaced brackets thereon supporting respectively, first, a plurality of longitudinally movable lace-point rods, second, a plurality of operating levers for the respective rods, and third, a plurality of tensioning springs for the respective levers, each of said tensioned levers acting axially against an end of its respective rod to maintain its opposite rod end in contact with said shifting plate.
2. In combination with a full-fashioned knitting machine having a lace-point-rod shifting plate, a rockable lace-clock mechanism comprising, a narrowing shaft, a plurality of point-rod supporting brackets, a lever-mounting bracket, and a spring-attaching arm, all carried by said narrowing shaft, a plurality of longitudinally movable lace-point-rods separately mounted in said supporting brackets, a plurality of levers, one for each rod, intermediately pivoted in said lever-mounting bracket, and a plurality of springs, one for each lever, connecting ends of the levers to said attaching arm, said springs acting individually to axially engage each opposite lever end with an end of its respective point-rod to longitudinally move the latter so as to maintain its opposite rod-end in contact with said shifting plate.

In testimony whereof I affix my signature.
MELCHIOR ZWICKY.
